UNITED STATES PATENT OFFICE.

HARRY C. WILLIAMS, OF ADRIAN, MICHIGAN.

STROPPING APPARATUS.

Application filed October 13, 1921. Serial No. 507,449.

To all whom it may concern:

Be it known that I, HARRY C. WILLIAMS, a citizen of the United States, and a resident of Adrian, in the county of Lenawee 5 and State of Michigan, have made an Invention Appertaining to Stropping Apparatus; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to blade stropping devices and particularly to one for use in stropping razor blades, and has for its object the provision of a simple, improved and efficient device of this character which is 20 easily operable to quickly strop a blade placed in connection therewith.

The invention is fully described in the following specification, and while, in its broader aspect, it is capable of embodiment 25 in numerous forms, a preferred embodiment thereof is illustrated in the accompanying drawings, in which,—

Figure 1 is a side elevation of a stropping device embodying the invention. Fig. 2 is 30 a cross-section thereof on the line 2—2 in Fig. 1. Fig. 3 is a side elevation of the blade holder carriage removed from the device and with the shift rack removed therefrom. Fig. 4 is a perspective view of the 35 shift rack used in connection with the carriage. Fig. 5 is a face view of the perforated strop preferably used in connection with the device, and Figs. 6 and 7 are bottom and top views of the device with a part 40 of the latter broken away.

Referring to the drawings, 1 designates a straight guide-strip of any suitable stiff material, such for instance as a thin strip of hard wood or pressed fiber board, having 45 at one end an eye 2 for attaching it to a hook and at its lower end a handle 3. Plates 4, 4, in the present instance of U-shape, are rigidly secured to the guide strip 1 near its opposite ends as by bolts 5 with the side 50 edges or leg portions of the plate projecting beyond the edges of the guide strips, as indicated, and with the legs of the two plates projecting toward each other.

Two posts 6 rigidly project in the same 55 direction from each plate 4 at right angles

to the faces of the plates and cooperate to adjustably and rigidly carry a stiff stropping board or member 7 at one side of the guide-strip 1 in parallel relation thereto. The ends of the board 7, in the present instance, are forked, with the furcations thereof secured to respective posts 6 by bolts, as shown, or in any other suitable manner. The board 7 is provided at its inner side with a stropping surface 8, preferably of leather, having a multiplicity of holes or sockets 9 therein for the purpose hereinafter described. The opposite side of the board 7 may also be provided with a stropping surface 10, which is adapted to 70 be placed in blade stropping relation to the guide strip 1 by a reversal of the board 7 on the post 6.

A carriage 11 is mounted on the guide strip 1 for reciprocatory movements longitudinally thereof, being provided at each end with a looped portion 12 for loosely embracing the guide strip 1 and having a handle 13 projecting centrally from its bottom away from the guide strip 5 to facilitate imparting reciprocatory movements to the carriage. The looped portions 12 of the carriage are connected at each end by side strips 14 and each side strip has a finger 15 projecting centrally therefrom toward the stropping board 7, and forming a bearing for the respective end of a cross shaft 16 disposed intermediate the guide strip 1 and stropping board 7 in parallel transverse relation thereto. A blade holder 90 or clip 17 is fixed to the shaft 16 intermediate the bearing fingers 15 for rocking movements with the shaft and the shaft is provided at each end without the respective bearing finger 15 with a pinion 18. 95

A rack member 19 is carried by the carriage 11 for limited reciprocatory movements relative thereto longitudinally of the guide strip 1. The sides of the rack member are disposed without the side strips 14 100 of the carriage and the ends thereof are provided with longitudinal slots 20 for receiving respective stop-pins 21 on the carriage. The sides of the rack members are rigidly connected by a cross-piece 22, which extends 105 crosswise of the carriage under the side strips 14 thereof. Each side of the rack member 19 is provided at its free edge with a series of rack-teeth 23 in mesh with a respective pinion 18 on the rock shaft 16 so 110

that a longitudinal movement of the rack member with respect to the carriage will impart a rocking movement in one direction or the other to the shaft 16 and blade holder 17. The rack member 19 is shifted at the limit of each stroke of the carriage on the guide strip 1 by reason of a pin or other obstruction 24 on the edge of the guide strip striking the projected ends of the rack member 19 slightly before the carriage has reached the limit of its stroke so that the rack member is held stationary while the carriage completes its stroke, thereby imparting a rocking movement to the shaft 16 to reverse the position of the blade holder. The blade holder 17 is intended to have trailing action with respect to the movement of the carriage and the shifting of the blade holder at the limit of a stroke places it in position for the return trailing movement. The plates 4 are of U-shape in the present instance to enable the carriage to enter the loop or recess thereof at the limit of each stroke and the stropping board 7 is forked at each end to provide an opening in which the shifting movement of the blade holder and blade carried thereby may take place.

While a blade 25, if desired, may be carried directly by the holder 17, it is shown, in the present instance, as carried by a separate holder or clip member 26, that is removably inserted within the holder 17. A blade which is carried by the holder 17 is held in proper relation to the stropping surface by posts 27 one of which is provided on each loop portion 12 of the carriage in position to project toward the stropping board, each post 27 being adjustable to regulate the pressure with which a blade supported indirectly thereby, is held against the stropping surface, and also to regulate the bevel of the blade. It is evident that when the blade holder is in one trailing position with respect to the carriage it is supported by one of the posts 27 and when in its other trailing position is supported by the other post. In order that the carriage may be held stationary with respect to the guide strip during the placing of a blade in engagement with the holder or its removal therefrom, the carriage is provided at one end with a set-screw 28, which may be turned into holding engagement with the guide strip 1. 29 designates a guard which is secured to the guide strip 1 at the handle end thereof.

It is found in practice that better sharpening results are obtained if the stropping surface is provided with holes or sockets 9, as the provision of holes in such surface tends to exert a suction action on the edge of a blade drawn thereover and materially facilitates the forming of a sharp edge on the blade.

65 In the use of my device it is preferable to

secure the carriage 11 at the upper end of its stroke during the placing of a blade in or the removal of the same from the holder, such security being effected by a tightening of the screw 28 against the guide strip 21. When a blade has been secured in position within the holder 17, the operator moves the carriage downward to effect a drawing of the trailing blade across the stropping surface in properly regulated pressure contact therewith. When the carriage is near the limit of its down stroke the then forward end of the rack member 19 strikes the adjacent pins 24 on the guide strip, thereby holding the rack member stationary during the completion of the stroke of the carriage and causing a rocking of the shaft 16 and blade holder 17 to reverse the position thereof by reason of the pinions 18 traveling along the rack teeth 23. The stroke of the carriage is then reversed and when near the limit of its upper stroke the rack member strikes the adjacent pins 24 and is held stationary thereby during the completion of the up stroke of the carriage and the reversing of the position of the blade holder. It is evident that the posts 27 may be easily adjusted to regulate the bevel and also pressure of a blade against the stropping surface, as the posts 27 are threaded into the looped portions 12 of the carriage and are locked in adjusted position by lock-nuts 30. It is preferable, however, to adjust the stropping board 7 for pressure and the parts 27 for blade bevel.

I wish it understood that my invention is not limited to any specific construction, arrangement, or form of the parts, as it is capable of numerous modifications and changes without departing from the spirit of the claims.

Having thus described my invention, what I claim as new and desire to secure by Letters Patent, is,—

1. In a stropping device of the class described, a guide strip of stiff material, means carried by the strip and forming a stropping surface in rigid parallel relation to the guide strip and facing the same, a blade holder, means mounted on the guide strip for limited reciprocatory movements longitudinally thereof and carrying the blade holder in position to trail therefrom and for a blade carried thereby to bear at its edge against the stropping surface when the reciprocatory means is reciprocated, the blade holder being carried for rocking movements by the reciprocatory means, pinions carried by the blade holder at the rocking axis thereof, a rack member carried by the reciprocatory means for limited relative movements longitudinally thereof, and means carried by the guide strip for coating with the rack member at the limit of each stroke thereof when the reciprocatory means is reciprocated to impart a shifting movement to the blade 130

holder to change its trailing movement with respect to its carrying means.

2. In a stropping device of the class described, a guide strip of stiff material, means carried by the guide strip and forming a stropping surface in rigid parallel relation to the guide strip and facing the same, a carriage mounted for limited reciprocatory movements on the guide strip, a rack member carried by the carriage for limited reciprocatory movements longitudinally thereof and having a rack portion at each side, a shaft carried by the carriage for rocking movements relative thereto, pinions fixed to the shaft and in engagement with the respective rack portions of the rack member, a blade holder fixed to the shaft and adapted to trail

in either direction therefrom in position to hold a blade carried thereby with its edge in engagement with the stropping surface when moved across the same, means carried by the carriage for supporting the blade holder in predetermined relation to the stropping surface in either trailing position of the holder, and means associated with the guide strip for coaction with the rack member to impart relative movements to the carriage and rack member at the limit of each stroke of the carriage to effect a reversal of the trailing position of the blade holder. 30

In testimony whereof I have hereunto signed my name to this specification.

HARRY C. WILLIAMS.
